UNITED STATES PATENT OFFICE.

HERMAN V. BERNHARDT, OF NEWARK, NEW JERSEY.

JEWELER'S GAGE.

950,221.

Specification of Letters Patent. Patented Feb. 22, 1910.

Application filed July 13, 1909. Serial No. 507,296.

To all whom it may concern:

Be it known that I, HERMAN V. BERNHARDT, a citizen of the United States, residing at Newark, in the county of Essex and State of New Jersey, have invented certain Improvements in Jewelers' Gages, of which the following is a specification.

The objects of this invention are to provide a gage of improved construction which can be used for determining the sizes and weights of stones which are to be set, and also the sizes of mountings or settings for said stones; to provide such a gage reading upon one of its faces in terms of weight as 10 carats, and upon its other face in terms of size, such as millimeters, to provide such a gage which shall be very compact and convenient to carry in the pocket or elsewhere; to secure great simplicity of the gage, both 15 in its construction and in its use; to thus provide a convenient gage by which stones and their settings can be measured quickly and accurately, and to obtain other advantages and results as may be brought out in 20 the following description.

Referring to the accompanying drawings, in which like numerals of reference indicate corresponding parts in each of the several figures, Figures 1 and 2 are face views of 25 my improved gage from its opposite sides, showing the carat and millimeter readings, respectively, and Fig. 3 is a transverse section of the gage on line 3—3 of Fig. 2.

In said drawings, 15 indicates the body 30 portion of my improved gage, which I have shown as approximately circular with a large opening 16 in the middle, although it will be understood that the body portion 35 might be of other shapes. Near the outer edge of the said body portion or plate 15 is a series of outside-caliper apertures 20, 21, 22, 23, etc., and from said outer edge opposite the said apertures project inside-caliper projections 40, 41, 43, etc., the inner edge of the body portion around the opening 16 providing a finger grasp or 40 means for holding and handling the gage.

The body portion 15 is preferably formed 45 of thin sheet material, and all in one piece, although it might be otherwise. The outside-caliper apertures 20, 21, 22, etc., form a graduated series of sizes, as will be understood, any one of which may be selected and used in measuring a gem. On 50 one side of the body portion 15 of the gage, these graduated openings are marked in

terms of carats, or the weights of stones, as shown in Fig. 1, while on the other side of the body portion 15 the markings are in terms of size, or in millimeters, as shown in Fig. 2. Each one of the said outside-caliper apertures 20, 21, 22, 23, etc., is preferably circular in shape, as shown, and all said apertures are arranged in close proximity to the outer edge of the body portion 65 or plate 15.

From the outer edge of the body portion or plate 15, at points directly opposite the outside-caliper apertures 20, 21, 22, etc., project narrow necks 60, 61, 62, 63, etc. 70 These necks are preferably in longitudinal alignment each with a line drawn through the center of the adjacent outside caliper aperture perpendicular to the peripheral edge of the body portion 15, or substantially 75 radial lines in the form of gage illustrated in the drawings.

At the outer end of each neck 60, 61, 62, etc., is an inside caliper disk 80, 81, 82, 83, etc., respectively, and the disk at the outer 80 end of each neck is of the same size as the outside-caliper aperture at the base of said neck. The markings above described upon the sides of the body portion or plate 15, adjacent to the outside-caliper apertures 85 40, 41, 42, etc., therefore apply equally well to the inside-caliper disks 80, 81, 82, etc. Two series of markings are thus avoided, without any uncertainty or confusion to the operator, who always knows 90 that any inside-caliper projection is of the same size as the outside-caliper aperture to which it is adjacent.

My improved gage is of especial advantage to jewelers and stone-setters, since in 95 fitting a stone to a setting it is necessary only to find the aperture 20, 21, 22, 23, etc., through which the stone passes, and then select a setting into which the adjacent inside-caliper projection fits. No time is 100 lost nor inconvenience and confusion caused by having to pass a considerable distance from one caliper means to the other, or over any intervening caliper means, in using my improved gage. Furthermore, a 105 workman having one of my improved gages can instantly translate measurements from carats to millimeters, or vice versa, by simply looking on the other face of the gage. As for instance, if he is given carats and wishes 110 to work to millimeters, he looks up the given carat measurement on the face of the gage

and then reads the equivalent size in millimeters from the opposite face. Also my improved gage will serve for both precious stones (which are measured in carats) and for imitation stones (which are measured in millimeters), and thus takes the place of two gages.

Having thus described the invention, what I claim is:

10. 1. A gage comprising a plate having in itself adjacent to one of its edges an outside-caliper aperture entirely surrounded by the plate, a neck projecting from said edge of the plate in a direction away from said aperture and opposite said aperture with respect to said edge, and an inside-caliper member at the outer end of said neck of the same size as said aperture, said neck being narrower than said inside-caliper member.
15. 2. The hereindescribed gage, comprising a plate having in itself a series of outside-caliper apertures, a series of necks projecting from the edge of said plate, and inside-caliper members at the outer ends of said necks, the two series of inside-caliper members and outside-caliper apertures being in separated lines extending in the same direction and each aperture being

opposite an inside-caliper member of the same size.

3. The hereindescribed gage, comprising a body portion having in itself adjacent to its edge a series of outside-caliper circular apertures, a series of necks projecting from said edge of the body portion, each in central longitudinal alinement with the diameter of an aperture, and inside caliper disks at the outer ends of said necks, each disk being the same size as the aperture with whose diameter the neck supporting said disk is in alinement.

4. The hereindescribed gage, comprising a substantially circular body portion of sheet material having in itself adjacent to the edge a series of outside-caliper apertures, a series of necks projecting from the edge of said body portion and inside-caliper disks at the outer ends of said necks, the center of an aperture being in substantially the same radial line of said circular body as the center of a disk and each aperture and disk thus in radial alinement being of the same size.

HERMAN V. BERNHARDT.

In the presence of—

RUSSELL M. EVERETT,
FRANCES E. BLODGETT.
